(57) **CLAIM**

The ornamental design for hearing protector ear cups, as shown and described.

DESCRIPTION

FIG. 1 is a perspective view of hearing protector ear cups showing our new design;

FIG. 2 is a front view thereof, the rear view being a mirror image;

FIG. 3 is a right side view thereof, the left side view being a mirror image;

FIG. 4 is a top view thereof; and,

FIG. 5 is a bottom view thereof.

Portions of the drawings shown in broken lines form no part of the claimed design.

1 Claim, 4 Drawing Sheets
